CONVERTIBLE BABY CARRIAGE OR SIMILAR ARTICLE

Jacob Berger, New York, N. Y.

Application June 27, 1951, Serial No. 15,692

Term of patent 14 years

(Cl. D14—14)

To all whom it may concern:

Be it known that I, Jacob Berger, a citizen of the United States of America, residing at New York, New York, have invented a new, original, and ornamental Design for a Convertible Baby Carriage or Similar Article, of which the following is a specification, reference being had to the accompanying drawing, forming part thereof.

In the drawing:

Figure 1 is a front perspective view of the convertible baby carriage or similar article, showing my new design;

Fig. 2 is a front perspective view of the baby carriage body removed from its running gear; and

Fig. 3 is an end view of the design shown in Fig. 1.

I claim:

The ornamental design for a convertible baby carriage or similar article, as shown.

JACOB BERGER.
